MOISTENING APPARATUS

Robert F. Morrison, Oak Park, Ill., assignor to
 Ditto, Incorporated, Chicago, Ill., a corpora-
 tion of West Virginia

Application July 17, 1939, Serial No. 284,947

2 Claims. (Cl. 91—50)

This application is a continuation in part of my co-pending application Serial No. 268,844, filed April 19, 1939.

The invention relates to moistening apparatus and particularly to moistening apparatus adapted to be incorporated in duplicating machines to moisten copy sheets with a solvent for copying ink.

One form of the invention is embodied in a duplicating machine in which a master sheet, which has the data to be duplicated written or typewritten in reverse thereon with copying ink, is attached to a duplicating drum, the copy sheets being pressed against the master sheet one by one by a pressure or platten roller. Each copy sheet is moistened with a solvent for the copying ink as it is advanced to the bight between the duplicating drum and the pressure or platen roller, and a sufficient amount of the ink adheres to the copy sheet to make a good copy in positive.

A primary object of the invention is to provide improved means for applying the solvent to the copy sheets so that each copy sheet will be provided with a thin film of the solvent of substantially equal thickness throughout immediately before the copy sheet is pressed against the master sheet.

Other objects and advantages will become apparent as the following detailed description progresses, reference being had to the accompanying drawings, wherein—

Fig. 1 is a longitudinal vertical section taken through a duplicating machine which has moistening mechanism embodying the invention;

Fig. 2 is an enlarged fragmentary transverse section taken on line 2—2 of Fig. 1;

Fig. 3 is a fragmentary section taken on line 3—3 of Fig. 2;

Fig. 4 is a fragmentary section taken on line 4—4 of Fig. 2;

Fig. 5 is a fragmentary section taken on line 5—5 of Fig. 4;

Fig. 6 is a fragmentary section taken on line 6—6 of Fig. 3;

Fig. 7 is a fragmentary section taken on line 7—7 of Fig. 6;

Fig. 8 is a fragmentary section taken on line 8—8 of Fig. 7;

Fig. 9 is a fragmentary section taken on line 9—9 of Fig. 5;

Fig. 10 is a fragmentary section taken on line 10—10 of Fig. 9;

Fig. 11 is a fragmentary section taken on line 11—11 of Fig. 9;

Fig. 12 is a plan elevation, partly in section, of

a roller which embodies a modified form of the invention;

Fig. 13 is a section taken on line 13—13 of Fig. 12;

Fig. 14 is a fragmentary longitudinal section taken through a roller which embodies another form of the invention, and

Fig. 15 is a plan view of a roller embodying another form of the invention.

Referring first to Figs. 1 to 11, inclusive, wherein a preferred embodiment of the invention is illustrated as it is employed in a duplicating machine, the reference character 10 designates generally the frame of the machine. 11 is a duplicating drum to which a master sheet 11a may be attached by means well known to those skilled in the art. The master sheet 11a may be made by placing it in a typewriter with a carbon sheet backing it so that, when one types, the data to be duplicated appears in reverse upon the back surface of the master sheet. Obviously, when copy sheets are pressed against the master sheet in the proper manner, the copy sheets will have the data to be duplicated on them in positive.

12 is a pressure or platen roller for pressing the copy sheets against the master sheet carried by the drum 11. A stack or pile of copy sheets 12a is shown in Fig. 3. Obviously, if the copy sheets are advanced one by one to the bight between the drum 11 and the pressure or platen roller 12, the roller 12 will press the copy sheets against the master sheet 11a carried by the drum 11.

The roller 12 frictionally engages the drum 11 and is driven thereby. The drum 11 is driven by means including a crank (not shown) which is mounted on the outer end of a stub shaft 14 having a pinion 16 fixed to it. The pinion 16 meshes with a gear 18 mounted upon a shaft 19 which, in turn, is mounted in the frame 10. The drum 11 is constrained to rotate with the gear 18. A gear 20 disposed concentric with the shaft 19 is constrained to rotate with the drum 11 and meshes with an idler pinion 22 which, in turn, meshes with a pinion 23. The idler pinion 22 is journaled upon a stub shaft 24 projecting from the frame 10. The pinion 23 is fixed to a shaft 27 which has its ends rotatably journaled in the frame 10. Fixed to the shaft 27 is a combined moistening and feeding roller 28 which frictionally engages a second feeding roller 29, the construction being such that the rollers 28 and 29 will advance copy sheets to the bight between the drum 11 and the platen or pressure roller 12. The roller 29 is fixed to a

shaft 30 which has its ends rotatably journaled in bearing devices 31 mounted in the free ends of levers 32 which are pivoted upon pins 33 projecting from the frame 10. The levers 32 are provided with toothed extensions 34. Springs 35 have ends adjustably engaging the toothed extensions 34 and have their other ends fixed to pins 36 projecting from the frame 10. Obviously, the springs 35 may be adjusted to vary the pressure with which the roller 29 is urged against the roller 28.

During the operation of the machine, the combined moistening and feeding roller 28 is supplied with solvent by a roller 40 mounted upon a shaft 41 which has its ends rotatably journaled in bearing devices 41a which are mounted in the lower ends of levers 42, the levers 42 being pivoted intermediate their ends by pins 43. Pivoted to the upper ends of the levers 42 by pins 44a are pins 44 which are screw-threaded at their free ends to receive knurled nuts 45. The pins 44 project through apertures provided in lugs 46 which project, in turn, from plates 47 secured to the frame 10 by the pins 43 and the pins 33 (Figs. 3, 7 and 8). Associated with each of the pins 44 is an L-shaped bar 48 provided with an aperture 48a through which the pin 44 projects, the aperture 48a being formed in a portion of the bar 48 identified by the reference character 48b. Disposed around each pin 44, and interposed between the associated part 48b of the associated bar 48 and the associated lug 46, is a compression spring 49 which urges the bar 48, the nut 45 and the pin 44 to the left (Fig. 3) so that the levers 42 are urged yielding-ly in a counterclockwise direction (Fig. 3) to hold the roller 40 in contact with the roller 28. The force with which the roller 40 is urged against the roller 28 may be varied by manipulating the nuts 45 to adjust the compression springs 49. To prevent the bars 48 from rotating around the axis of the pins 44, the lugs 46 are provided with slots 46a in which the bars 48 slide. A bushing 46b is provided in each of the lugs 46, the construction being such that the pins 44 are slidably and somewhat loosely journaled in the bushings 46b (Fig. 8). The bars 48 are preferably provided with indicia 48c and 48d, the indicia being preferably the letters "L" and "D," respectively, as abbreviations of the words "Light" and "Dark." The indicia indicate to the operator the direction in which the bars 48 should be displaced to increase or decrease the intensity of the copies being produced by the machine. It will become apparent as this description progresses that the more pressure with which the roller 40 engages the roller 28, the fainter the copies will be.

As illustrated clearly in Figs. 3, 4, 9 and 11, the roller 40 is disposed in a tray 75 which is preferably formed of sheet metal, the construction being such that a small quantity of solvent, as indicated at 76 in Fig. 3, may collect to a sufficient depth in the tray 75 so that the lower portion of the roller 40 will be immersed in it, and when the roller rotates the entire cylindrical surface thereof will become moistened with the solvent.

Any suitable means may be provided for supplying the solvent to the tray 75, but in the preferred embodiment of the invention a supply of solvent is maintained in a receptacle or tank 78 mounted in the frame 10, (Fig. 1). Pump means 79 projecting through the tank 78 is adapted to pump the solvent through a tube 80,

10 a check valve 81 and a flexible tube 82 to a metallic tube 83 which communicates with an intermediate portion of a metallic tube 83a which has its ends bent to discharge into the ends of the tray 75, the tray 75 having end walls 75a through which the ends of the tube 83a project (Fig. 2). To maintain the solvent 76 at a predetermined level in the tray 75, a drain pipe 88 is provided, which drain pipe 88 is of the same shape as the pipe 83a and has its bent ends communicating with the tray 75 through the end walls 75a. Connected to the drain pipe 88 intermediate its ends is a downwardly extending metallic tube 88a which is connected by a flexible tube 88b to the tank 78. The ends of the drain pipe 88 are disposed in the end walls 75a at such a height as to insure the proper level of solvent in the tray 75.

15 The means for actuating the pump mechanism 20 79 preferably comprises a lever 92 pivoted upon a pin 93 projecting from the frame 10. The lever 92 is oscillated by a lever 94 also pivoted upon the pin 93, the lever 94 being provided at its free end with a roller 95 which rides upon a cam or disk 96 constrained to rotate with the drum 11. The disk 16 is provided with a notch 97 into which the roller 95 is urged by a spring 98 when the notch registers with the roller 95. Obviously, as the disk is rotated the roller 95 moves into and out of the notch 97 and causes the lever 94 to oscillate and the lever 94, in turn, oscillates the lever 92 with the aid of a spring 100 forming part of the pump mechanism 79. No further description of the pump mechanism 79 or of the apparatus for actuating it need be given, as the details of construction are illustrated in issued United States Letters Patent 2,135,824 granted Nov. 8, 1938 to Alfred Marchev.

25 As is best shown in Figs. 2 and 6, the end walls 30 75a contact the inner surfaces of the plates 47, the end walls 75a being preferably spot welded to the plates 47. It will be noted that the end walls 75a are relatively high in height as compared to the portion of the tray adapted to hold the solvent. 35 Pivoted to the end walls 75a by pivoting devices 101 is a cover plate 102 which, when it is in its closed position, has its free end resting upon a baffle plate 103 extending between and fixed to the end walls 75a. It will be noted that the lower portion of the baffle plate 103 is curved to fit rather closely around the roller 28. Means 50 is provided for locking the cover plate 102 in its closed position, this means preferably comprising a latch member 102a which is engageable with the baffle plate 103 and which may be displaced from its functionally operative position to its functionally inoperative position, or vice versa, by a pin 104.

45 The machine is provided with a copy sheet tray 60 110 (Figs. 1 and 3) upon which the stack of copy sheets 12a may be placed and advanced one by one to the bight between the rollers 28 and 29. That end of the tray 110 adjacent the rollers 28 and 29 is inclined upwardly at a slight angle and forms a throat with the bottom wall of the tray 75 through which the copy sheets must pass on their way to the bight of the rollers 28 and 29.

55 Improved means is provided for preventing the solvent from accumulating on the ends of the roller 40 to be transferred to the ends and the bight of the rollers 40 and 28. This means preferably comprises plates 115 fixed to the inner surfaces of the end walls 75a by rivets 116 and 117 (Figs. 3, 9 and 11). Movably mounted on the lower ends of the plates 115 are wiper members

118 which are preferably formed of brass, although other substances may be employed. The wiper members 118 are urged against the ends of the rollers 40 and 28 by compression springs 119. The surfaces of the wiper members 118 contacting the ends of the rollers 28 and 40 are preferably chromium plated, as indicated at 120. The wiper members 118 are slidably journaled on pins 121 projecting from the plates 115. The wiper members 118 prevent or retard the accumulation of solvent on the ends of the rollers 40 and 28 when the machine is in operation.

The rollers 28, 29 and 40 are made preferably of resilient material, the rollers 40 and 28 being preferably formed of a synthetic rubber known by the trade name "Perbunan," sold by Advance Solvents & Chemical Company, of New York city. The roller 29 is preferably formed of black synthetic sponge rubber known by the trade name "Neoprene."

The rollers 28 and 40 are preferably of solid construction, although excellent results have been obtained with rollers formed of synthetic sponge rubber. The rollers 28 and 40 preferably have a "Shore hardness" of 55 to 60. The roller 40 is preferably ground on its cylindrical surface to a rough finish, the roller 28 being ground to a smoother finish.

In some instances it may be desirable to form all of the rollers 28, 29 and 40, or some of them, of rubber or rubber compounds.

The operation of the above described apparatus is substantially as follows:

The machine is driven manually by means of the crank (not shown) and during such operation of the crank the drum 11 rotates and, in turn, drives the platen roller 12. Rotation of the drum 11 causes rotation of the disc 96 so that the pump mechanism 79 is actuated. The pump delivers the solvent to the tray 75 and the roller 40 driven by frictional engagement with the roller 28 delivers solvent to the roller 28 in such manner that a thin film of solvent is left on the face portion of the roller 28 below the bight between the two rollers. The roller 28 rotates in a counterclockwise direction (Figs. 3 and 9) and drives the roller 29 in clockwise direction (Figs. 3 and 9). The thickness of the film is controlled by adjusting the nuts 45. The copy sheets on the copy sheet tray 110 may be advanced one by one to the bight of the rollers 28 and 29 which advance the copy sheets to the bight between the drum 11 and the platen roller 12 so that the copy sheets are pressed against the master sheet one by one. As the copy sheets pass between the rollers 28 and 29 the roller 28 applies a thin film of the solvent upon the upper surface of each copy sheet. This solvent moistens the copying ink on the master sheet so that the data on the master sheet will be duplicated in positive on each copy sheet.

Referring now to Figs. 12 and 13 wherein a roller 140 is shown which may be employed in place of the roller 40 described above, the reference character 141 designates a shaft which is identical with the shaft 41 so that it may be introduced into the mechanism shown in Figs. 1 to 11, inclusive. The roller 140 is preferably made of the same material as the roller 40 but is provided with inserts 142 in its ends to lessen the friction between the ends and the chromium plated surfaces of the wiper members 118. These inserts are preferably made from the same material as the body of the roller but are impregnated with graphite, the mixture containing

about 20% graphite by weight in its preferred form although mixtures of 30% graphite have given satisfactory results and mixtures containing from 10% to 40% of graphite by weight are contemplated. Each insert 142 preferably comprises a perforated disc 143 having a plurality of pin-like projections 144 formed integrally with the disc. The discs are imbedded in the ends of the roller 140 and the pin-like projections have their outer ends flush with the end surfaces of the roller 140 so that they are engageable by the wiper members 118.

It is contemplated that the rollers 28 will be provided with inserts of graphite-impregnated material similar to the inserts 142 described above.

In Fig. 14 a roller is shown which embodies another form of the invention. The roller is identified by the reference character 150 and may be substituted for the roller 40, the roller 150 being mounted on a shaft 151 which is identical in construction with the shaft 41 described above. The roller 150 has collars 152 at the ends of the main body of the roller, the collars 152 being formed of graphite-impregnated material of the same composition as the inserts 142 of the roller 140. The collars 152 undergo a curing treatment assembled with the main body portion of the roller 150 so that the collars 152 become substantially integral with the main body portion.

The method of preparing the rollers 40, 140 and 150 is substantially as follows: after the material from which the rollers are formed has been cured the rollers are ground to a rough finish and are then immersed in the solvent employed in the duplicating machine preferably about forty-eight hours but at least twenty-four hours, after which the rollers are permitted to dry for about twenty-four hours. The end surfaces of the rollers are then dipped into a saturated chlorine solution for from three to five minutes, the end surfaces having been ground smooth at some time prior to the dipping step. The saturated chlorine solution also causes the end surfaces to become smooth so that there will be a minimum of friction between them and the wiper members. After the end surfaces have been treated with the chlorine solution the rollers are ground to exact size and are left with a rough finish as stated above.

The roller 28 is treated in substantially the same manner as the rollers 40, 140 and 150 but in the final grinding a smooth cylindrical surface is provided on it in contrast to the relatively rough cylindrical surfaces provided upon the rollers 40, 140 and 150.

In the preferred embodiments of the invention the shafts 41, 27, 141 and 151 have their ends chromium plated to reduce friction and wear.

In Fig. 15 a roller 160 is shown which may be employed in place of the roller 40. The roller 160 is mounted on a shaft 161 which is identical in dimensions with the shaft 41. The ends of the roller 160 are tapered as at 162. A roller similar to the roller 160 but having a diameter equal to that of the roller 28 will be substituted in the same machines for the roller 28. The tapered ends of the rollers of the type illustrated in Fig. 15 will have a tendency to give the solvent on the upwardly moving face of the pick-up roller 160 an initial movement longitudinally of the roller away from its ends so as to bring such

solvent into position to be spread evenly by the cooperating forwarding roller.

The roller 29 of the machine illustrated in Figs. 1 to 11, inclusive, is preferably formed from sponge neoprene, the holes or voids in the sponge neoprene being relatively minute to provide a surface on the roller which will be sufficiently porous or absorbent to remove excessive solvent at the bight between the rollers 28 and 29. The roller 29 is ground to size.

While the form and arrangement as shown are preferred, the invention is not to be limited thereto except as the claims may be so limited, it being understood that changes might be made in the arrangement without departing from the invention.

I claim:

1. In a duplicating machine, apparatus for applying solvent for copying ink to copy sheets, said apparatus comprising a receptacle for holding a supply of the solvent, a resilient roller partially immersed in said solvent, a second resilient roller contacting said first-mentioned roller and adapted to engage and advance said copy sheets, the ends of the first-mentioned roller and said

second roller being impregnated with graphite, means for rotating said second roller, a third roller driven by said second roller through frictional engagement therewith, said copy sheets being advanced between said second roller and said third roller, and means engaging the ends of the first-mentioned roller and said second roller for wiping solvent therefrom.

2. In a duplicating machine, the combination 10 of a resilient roller rotatably mounted in position and having its end portions impregnated with graphite, a second resilient roller contacting said first-named roller, a third roller in contact with said second roller so as to be driven by frictional engagement therewith for advancing copy sheets between said second and third rollers, means for delivering solvent into the bight between said first-named and said second rollers above their line of contact as said rollers rotate, and wiper means engaging the ends of said first-named and said second rollers for preventing the accumulation of solvent on the ends of said first-named roller.

ROBERT F. MORRISON.
